United States Patent Office.

JAMES KIRKLEY, OF CHICAGO, ILLINOIS, ASSIGNOR TO HIMSELF AND
HUGH GRAY.

Letters Patent No. 82,329, dated September 22, 1868.

IMPROVED CAR-BRAKE ATTACHMENT.

The Schedule referred to in these Letters Patent and making part of the same.

TO ALL WHOM IT MAY CONCERN:

Be it known that I, JAMES KIRKLEY, of Chicago, in the county of Cook, and State of Illinois, have invented a certain new and improved Mode of Operating Railroad-Car Brakes; and I do hereby declare that the following is a full, clear, and exact description thereof, reference being had to the accompanying drawings, making a part of this specification, in which—

Figure 1 is a front view of one-half of a railroad-car platform, showing a portion of the hand-rail, the brake-standard, the ratchet, and the pawl-box.

Figure 2 is a longitudinal section, taken vertically through the platform of a railroad-car, showing a side view of the same parts illustrated in fig. 1.

Figure 3 is an enlarged vertical section, taken lengthwise through the pawl-box, as indicated by the course of red line $y\ y$ in fig. 4.

Figure 4 is a horizontal section through the pawl-box, as indicated by the course of line $z\ z$ in fig. 3.

Similar letters of reference indicate corresponding parts in the several figures.

This invention relates to certain new and useful improvements on releasing and arresting-devices which are applied to brake-standards of railroad-cars and coaches.

The object of the invention is to provide for enclosing the pawl; or other equivalent releasing and arresting-device of a brake-standard, within a case or box, and employing a treadle, for releasing the said pawl from its ratchet-wheel upon the brake-rod when it is desired to free the brakes, said parts being so constructed that all liability to accident is prevented from an exposure of pawl at such points, as will be hereinafter explained.

Another object of my invention is to so construct the pawl-and-ratchet wheel of a brake-standard that when the pawl is raised free from its ratchet, it will be automatically arrested or held in this position until the brake-standard is turned to wind up the brake-chain, when said pawl will be caused to engage with the ratchet-wheel again, so as to retain the brakes at any point during the act of applying them, as will be hereinafter explained.

To enable others skilled in the art to understand my invention, I will describe its construction and operation.

In the accompanying drawings, A represents a car-platform, B B' the hand-rail, and C the brake-standard or spindle, with a hand-wheel C' on its upper end, all of which parts may be constructed in the usual well-known manner.

The standard C is supported in a vertical position by an eye-bracket, a, projecting from the hand-rail B' and also by a stirrup, G, which is bolted to the bottom of the platform A, as shown in figs. 1 and 2. These supports allow the standard C to be rotated freely either toward the left or right.

To the standard C, on top of the platform A, a wheel, D, is keyed, having ratchet-teeth formed upon its upper surface, and a rebate in its lower circumferential edge, which rebate has a tooth, b, that is designed to serve as a releasing-trip for a pawl, H, when it is desired to have this pawl engage with the teeth of ratchet-wheel D, as will be hereinafter explained.

The pawl H is constructed with a tail-extension, p, upon it, the rear extremity of which is adapted for receiving a latching-piece, g¹, as shown in fig. 3, when this pawl is free from the ratchet-teeth on wheel D.

Pawl H is pivoted at i to two ears, S, formed on a fixed plate, g¹, and through the tail-extension p an oblong hole is made for receiving through it the vertical stem f of a treadle, E.

Beneath the tail-extension p, and surrounding the treadle-stem f, is a coiled spring, g¹, which operates to throw up said extension, and thus engage the pawl with the ratchet-teeth on wheel D. A spring, f', also surrounds the treadle-stem f within spring g¹, which is designed for throwing up the treadle E when released from pressure of the foot of the brakeman.

Both springs, g¹ and f', are held in place against lateral displacement by a cupped elevation upon the fixed plate g, as shown in fig. 3.

The latch g^2 is pivoted in a slot made through the plate g , and acted upon by a spring, g^3 , so that when the treadle E is depressed, and the pawl H thus released from the wheel D , said latch will catch over the rear extremity of the tail of the pawl, and hold it in the position shown in fig. 3. When the pawl H is thus held by the latch g^2 , the brake-standard C , with its wheel D , is free to rotate either to the right or left.

This latch g^2 is designed to relieve the brakeman from the inconvenience of pressing with his foot upon the treadle E during the unwinding of the brake-chain c from the brake-standard.

For the purpose of releasing the pawl H from the latch g^2 , a sliding plate, h , is fitted into a recess, n , made in the bottom of the fixed plate g , and guided by studs t , passed through on oblong slots j made through said oblong plate. A short hooked stud, h' , is secured to the rear end of slide h , and extends up through the slot through plate g , in which latch g^2 is pivoted, so as to act upon this latch.

A right-angular arm, k , is pivoted in the recess n to plate g at the opposite end of the slide h , by pressing which arm in one direction, it will force the plate h backward, and cause the stud h' to disengage the latch from pawl H , thereby allowing the spring g^1 to engage the pawl with the ratchet-teeth on wheel D . That end of the angular arm k which is nearest the wheel D projects beyond the plate g , so as to be struck by the tooth b upon the circumference of wheel D , when this wheel is rotated.

The tripping and releasing-devices, with the exception of a portion of the ratchet-wheel D , are enclosed within a box, F , which, with plate g , is bolted down fast upon the platform, as shown in the drawings.

This box serves as a safety-guard to prevent accidents, which frequently happen upon the platforms of railroad-cars, in consequence of ladies' dresses catching upon the exposed pawls, as hitherto employed.

Said box also serves to keep out dust, ice, and snow from the enclosed devices, and protects them from injury from any external cause.

The treadle or foot-piece E for releasing the pawl from its ratchet-wheel, is fitted to work in a depression, d , formed in the crown of the box or case F , and this treadle is constructed with shoulders, e' , upon the lower end of its guide-stem, which keep it in place within its recess, and allow it to rise flush with the top surface of the box F when released.

While I prefer to employ the latching and releasing-devices for the pawl, in conjunction with an enclosing-case for this pawl, I do not confine my invention to this combination; as the pawl and treadle, with the ratchet-wheel and enclosing-case, may be used to advantage without said arresting and releasing-devices.

Having described my invention, what I claim as new, and desire to secure by Letters Patent, is—

1. A guard-box, F , adapted for enclosing the pawl and ratchet of a brake-standard, substantially as described.
2. The combination of a treadle, E , pawl H , and ratchet-wheel D , substantially as described.
3. Fitting the treadle E to the guard-box F , substantially as described.
4. A spring-latch, g^2 ; a pawl, H , ratchet-wheel D , a treadle, E , and means, substantially as described, for releasing the latch g^2 , by the act of turning said ratchet-wheel.

JAMES KIRKLEY.
